PULVERIZER

Joseph B. Gaffney, New York, N. Y., assignor to
Peabody Engineering Corporation, New York,
N. Y., a corporation of New York

Application June 20, 1935, Serial No. 27,501

2 Claims. (Cl. 83—11)

My invention relates to a method of and apparatus for reducing materials to a powdered condition.

It is well known that impact may be used in 5 pulverizers, to reduce the sizing of materials being treated, with relatively little power consumption. It is also well known that the product produced due to impact alone is not sufficiently fine for many purposes, and, that to produce a product that is sufficiently fine, it is necessary to supplement the effect of impact with attrition.

To further reduce the relatively fine particles produced by impact, which are too large for delivery from the mill as finished product, the 15 following means of providing attrition are generally employed. The particles are kept in circulation within the mill, are acted upon by the hammers or arms at high rotative speed, and/or the hammers or arms rub and drag through an accumulation of the relatively fine material 20 which collects in the mill.

Because of the small mass of these particles, the reaction offered by them to the hammers or arms is insufficient for their further economical reduction. Due to the high rotative speed of the 25 hammers or arms, air currents are set up within the mill and along the faces of the hammers or arms that are sufficient to materially reduce the chance of contact between the rotating hammers or arms and the particles. Because of the 30 small mass of the relatively fine particles and their inability to offer sufficient reaction unless effectively confined, the action of the hammers or arms in passing through or dragging over the relatively fine material that has accumulated 35 in the mill, is an inefficient means of effecting further reduction in size. Due to windage losses, high rotative speeds, dragging of the hammers or arms making contact with the material being treated at a maximum distance from the rotat- 40 ing shaft, the lack of confinement of the relatively fine material being treated to provide re- action by the particles to make the effect of the forces being exerted upon them efficient, and unnecessary continued circulation of these par- 45 ticles to be further reduced within the mill, attrition by such means is very uneconomical in power consumption, and inefficient in its ability to produce the quantity of fines so necessary for 50 many purposes.

One object of my invention is to provide a method by which impact and attrition are used in a single pulverizer, independent of each other.

A further object is to provide a pulverizer that 55 makes efficient use of the effect of impact and

does not require that the impact elements be used for providing attrition.

A further object is to provide a pulverizer, that discharges finished product as soon as it is received or produced, that delivers material too 5 small for efficient reduction by impact and yet too large to be finished product to an efficient means for further reduction by attrition as soon as it is received or produced, and delivers all other material to an efficient means for initial 10 reduction by impact.

A further object is to provide a pulverizer in which the impact means will not drag in the material being treated.

A further object is to provide a pulverizer in 15 which the relatively fine material ready for attrition will be confined in order that the means provided for attrition will be employed efficiently.

The invention will be understood from the 20 following description taken in connection with the accompanying drawing, in which Fig. 1 is a view in elevation, Fig. 2 a transverse section on the plane of the lines 2—2, of Fig. 1, and a part 25 view in elevation, Fig. 3, showing an alternate arrangement of impact means and air admis- sion.

Referring to the drawing, the method of operation, and the apparatus illustrated which is enclosed in a suitable housing, may for the convenience of description, be considered as divided into eight parts, designated generally by the letters A, B, C, D, E, F, G and H. The material to be pulverized enters at A, the rate of delivery being controlled or regulated by a suitable feed- 30 er, driven from the mill shaft by a suitable means, or independently driven. That part of the mill where the material is reduced by impact, for convenience called the impact zone, is design- 35 ated as B. Mill air entering the mill below the center of the rotating impact means is admitted 40 at C. One of the purposes served by this method of admitting mill air is to remove fines from the impact zone B, as they are produced. This prevents a possible wasteful use of power that 45 would result from the dragging of the impact means through material accumulating in the bottom of the impact zone B, if this method of air admittance were not used. This air also removes material reduced sufficiently by impact 50 for further treatment by attrition to the separating or classifying zone designated as D. In the separating or classifying zone the finished product is separated from that which requires further treatment by attrition, the finished prod- 55

uct leaving the mill at the mill outlet E, and the product requiring further reduction being delivered to that portion of the mill, for convenience called the attrition zone, and designated 5 as F. Auxiliary air for conveying may or may not be used depending upon the material being pulverized, or the purpose for which the pulverizer is being used. When auxiliary air is used, it will enter at the auxiliary air inlet designated 10 as G. Mill air, the finished pulverized product, and auxiliary air, if auxiliary air is used, will be discharged into a duct or suitable delivery means at H.

The apparatus as illustrated is particularly 15 adapted for pulverizing coal. It will be understood, however, that for this purpose and when used for pulverizing other materials the arrangement of apparatus may be varied. For example, auxiliary air may be omitted, the fan may be a 20 separate unit driven from the pulverizer mill shaft, or separately driven, the discharge of the mill may enter the suction side of a separately mounted fan or the discharge of a separately mounted fan may be connected to the mill air 25 inlet designated as C, or the fan may be omitted and the necessary air provided by the fan blades 16 attached to the disc 11. The power to drive the rotating parts of the apparatus may be supplied by a motor or any other suitable means, 30 and may be applied either above or below the pulverizer.

In the apparatus illustrated 1, is a suitable housing preferably provided with flanged and bolted connections not shown. The housing 1, is provided with an opening A to admit coal, an opening for air to enter at C, and a discharge outlet at E. Superimposed on housing 1, and either an integral part thereof, or flanged and bolted thereto, is a chamber enclosed in the supplementary housing 3, provided with an inlet for mill discharge at E, an inlet for supplementary air at G, and an outlet at H.

The motor 4, supported on the housing 3, drives the vertical shaft 5, through a flexible 45 coupling 6. The shaft 5 is supported by suitable bearings 7 and 8. Rigidly attached to the shaft 5 and suitably supported thereby, there is a fan rotor 9 provided with fan blades, and an adjustably mounted classifying bar 10, clamped to 50 the shaft by means of the bolts 10a. At the lower part of the shaft 5, also rigidly attached thereto, there is a rotating disc 11 carrying flexibly mounted hammers or arms 13 and, if desired, fitted with the fan-like blades 16. The 55 rotating attrition element 19, and its wearing surface 20, is supported by, is rigidly secured to, and rotates with the disc 11. The rotating parts 19 and 20 may if preferred, be independently supported by the shaft 5. The stationary wearing surface surrounding the impact zone B is lined with the replaceable wearing parts 14 and 15.

The stationary part of the attrition means 22, with its wearing face 23, is supported by brackets 65 24 securely attached to the stationary cone 17. The stationary cone 17 is rigidly attached to the housing 1 by means of the brackets 38. The adjustment of the space between the wearing surfaces 20 and 23 is provided for, if a space is 70 desired, by the adjusting means 25. A suitable number of springs 26 with means 27 for adjusting their pressures, exert pressure on the stationary part of the attrition device 22, through the brackets 28 rigidly attached to, or a part 75 of 22.

The protective covering 21, is provided as a means of protecting the shaft 5 from wear due to material collecting in the attrition zone, if such protection is found necessary. The stationary cone 18 rigidly secured to the housing 1, forms an enclosure for the classifying element 10, and an outlet 39, from the mill.

Attached to the casing 1 by suitable flanges and bolts not shown is a feeder housing 29. Material is delivered to the conveyor 30 through the hopper 31. The sprocket or pulley 32 is driven by any suitable means and causes the conveyor 30 to deliver material over the idling sprocket or pulley 33 to the discharge opening in the feeder housing 29 at 34. Material to be pulverized is delivered to the mill through the opening 35 in the mill housing 1. The adjustable gate 36 serves as a means of admitting a small amount of air to the mill and as a means of access to the pocket 37.

One or more means of access to the interior of the mill are provided through the opening or openings 40 in the housing 1. A cover or covers 41 are provided to close the opening or openings 40 when not in use.

For clearness the direction of flow of mill air entering the mill at 42 and leaving at 39, is shown by the solid arrows 12. The path of the supplementary air when used is shown by the dotted arrows 29. A removable portion 43 of 30 the cone 17 is provided for access to the adjustable classifying bar 10.

The illustration shows one impact element assembly 11 and 13, and one attrition device 19 and 22. In any mill one or more of either or 35 both assemblies may be used.

In the alternate arrangement of the impact zone, B¹, shown as a part view in elevation, Fig. 3, the brackets 44 supporting the flexibly mounted hammers 45, are rigidly mounted on the revolving disc 11a. The fan-like blades 16 are rigidly attached to the under side of the revolving disc 11a. A relatively small circumferential opening 46 is provided between the outer circumference of the revolving disc 11a and the stationary replaceable liner 47. A plurality of pegs or bars 48, spaced along the circumferences formed by the intersection of horizontal planes and the replaceable liner 47, form the stationary impact means. The pegs or bars 48 project inward from 50 47, and are located in horizontal planes spaced so that the hammers 45 will not contact the pegs or bars 48 when the mill is in operation. It will be understood that the impact means may take other forms and if preferred that the stationary impact means 14 and 15 shown in Fig. 1 may be used with the revolving impact means shown in Fig. 3, or that the stationary impact means shown in Fig. 3 may be used with the revolving impact means shown in Fig. 1. Air inlet openings 49, in the mill casing 1, admit air induced by the fan blades on the fan rotor 9. Fig. 1, to the air chamber 50, and into the mill through the relatively small circumferential opening 51.

A tube 52 connects the air space under the revolving disc 11a, with the U tube or manometer 53 containing a suitable liquid 54, responsive in its movement within the U tube or manometer 53 to air pressure variation in the air space below the revolving disc 11a.

Numbered parts in Fig. 3 also appearing in Fig. 1 are identical parts and that portion of the view in elevation not shown in Fig. 3 is identical with Fig. 1.

The operation is as follows:

Assume that coal is the material to be treated, that it is received in the condition it comes from the mine, that it has been crushed or screened to a suitable size to be delivered to the pulverizer. In this condition, the coal may be dry, or contain various percentages of moisture. It may be uniform in size, or it may be of such size as to contain a range from the maximum size determined upon as the limiting size to be fed to the pulverizer to fines of sufficiently small size to be considered suitable for delivery from the pulverizer without further reduction. The coal as received normally contains moisture and fine as well as coarse coal. Because this condition calls for the use of all the facilities provided for in the apparatus illustrated, it will be used in the description.

Heated mill air improves the efficiency of pulverizing when wet coal is being treated. To provide heated mill air, the air entering at C may be heated by any suitable means, such as passing the air through an air heater or other suitable means of heat transfer, taking hot air from air cooled furnace walls, diluting the mill air with hot air from any source, or diluting the mill air with hot flue gases.

Coal is delivered by the mill feeder at the rate desired. As the coal falls from the feeder it is carried into the mill at A by a current of air admitted through and regulated as to amount by the cleanout pocket gate 36. Tramp iron and other foreign materials, heavier than coal, which may cause damage if allowed to enter the mill with the coal, are too heavy to be carried into the mill by the air referred to, and instead are deposited in the pocket 31.

The direction of flow of the mill air is indicated by the solid arrows 12. That coal which is sufficiently fine for delivery to the attrition zone F and for delivery to the mill outlet E is carried by the mill air to these points. The coal too coarse to be carried off as it is delivered to the pulverizer at A by the mill air flow 12, falls to the impact zone B. It is acted upon by the hammers 13, supported by the rapidly rotating disc 11. The hammers are supported in a manner that they will extend outward as shown when the mill is in operation, and revolve on their own axes, to prevent damage when contact is made by them with foreign material such as metal that may enter with the coal. The effect of impact upon the coarse coal by the hammers 13, and the impact of the coal due to the motion imparted to it by the impact hammers 13 on the replaceable wearing parts 14 and 15 reduces its size. As the reduction in sizing of the coal progresses that part which has been reduced sufficiently is carried by the mill air 12 and delivered to either the mill outlet E or the attrition zone F, depending upon whether it is sufficiently fine enough for delivery from the mill as finished product, or requires further reduction by attrition. The hammers 13 and the removable wearing surfaces 14 and 15, may be of other forms, such as paddles in place of hammers 13, and pegs in place of wearing surfaces 14 and 15.

As the coal enters the mill at A, and is reduced by impact at B, the fines ready for delivery from the pulverizer and those ready for further reduction by attrition are delivered to the stationary cone 17. The cone 17, serves to form part of a separating or classifying chamber and also a means of delivering that portion of the coal ready for further reduction by attri-

tion, to the attrition zone F. The coarse particles entering the stationary cone 17 will fall out of the mill air currents 12, due to the air expanding in the separating chamber and losing velocity, due to gravity, and due to the change of direction of the air currents. The balance of the product as it passes upward carried by the mill air encounters the rapidly rotating classifying device 10, operating within the stationary cone 18. The classifying device 10 is adjustable vertically along the shaft 5 as a part of the means of fixing the fineness of the mill output. Due to the high rotative speed of the separating or classifying device 10, the air currents with the fines carried by them are caused to rotate with in the stationary cone 18, and because of the centrifugal force imparted to the heavier particles due to their greater mass, they are returned to the stationary cone 17 for delivery to the attrition zone F. The finished product passing the separating or classifying device 10, is delivered to the mill outlet E by the mill air currents 12.

The coal particles rejected by the separating or classifying device 10, and those falling out of the mill air currents passing through the space formed by the stationary cone 17, are delivered to the confining space forming the attrition zone F. Due to the high rotative speed of the surface 20, and the wedging angle formed by the surfaces of the wearing faces of 20 and 23, material collected in the attrition zone will be forced outward away from the center of the pulverizer. This action due to the confinement of the relatively fine material away from the influence of the mill air currents, the rubbing of the faces 20 and 23 on the material, and the effect of the rubbing of the material upon itself, will produce a product that has been treated effectively by attrition as to its fineness, and efficiently with reference to the power requirements. The fines leaving the attrition zone will not clog or impede the action of the impact pulverizing devices, since they are picked up by the mill air currents 12 as they are produced.

The blade 16 on the under side of the rotating disc 11 serves to assist the fan 9 in causing the mill air currents 12 to flow through the pulverizer, and keep the impact zone B clear of material that the hammers 13 and disc 11 might otherwise drag on. For some purposes it will be advantageous to omit fan 9 and use only fan blades 16 to furnish mill air.

Auxiliary air discharging at H with mill air and finished product, when used, enters at G, and its flow is indicated by the dotted arrows 29.

Suitable dampers not shown may be used in one or more of the following ducts, the mill air duct delivering air to C, the auxiliary air duct delivering air to G, and the duct taking the mill discharge at H, for the proper regulation of air flow.

For some materials it will be found advantageous to use the alternate arrangement of the impact zone B¹ as illustrated in the part view in elevation Fig. 3. This arrangement will be particularly advantageous when treating materials with a relatively high specific gravity, or in cases where it is necessary to limit the air used in the impact zone to the minimum that will prevent the dragging of the rotating impact elements in accumulation of the material being treated.

Air for use in the impact zone enters at C, induced by the fan like blades 16 attached to the

- under side of the revolving disc 11a. The air is delivered to the impact zone B through the circumferential opening 46. Additional air is admitted to the mill above the impact zone B¹, induced by the fan blades on the fan motor 8, Fig. 1, through openings 49 in the mill housing 1. This air enters the circumferential chamber 50, and is delivered from it into the mill through the circumferential opening 51.
- 5 10 If desired, the air entering at C may be controlled by suitable dampers, not shown, in the duct leading to C. The air entering through the openings 49 may be controlled by suitable dampers, not shown, in the duct leading from the discharge of the fan in the fan housing 8, at H, Fig. 1, or if preferred suitable dampers or control gates may be provided in the openings 49, or in a duct with manifold connections to the openings 49.
- 15 15 20 If the material being pulverized is of such a nature that a gas would serve the purpose better than air, for example, a gas that will not support combustion when grinding highly combustible materials, or a gas for combining with the material being treated during the process of pulverization, then gas or gases, gas and air, or gases and air, may be used as described for air in the foregoing. It is understood that the air or gas, or air and gas may be heated if desired to whatever temperature is found to give the best results.
- 25 25 30 The material to be pulverized is delivered to the mill by the same means as has been described in the foregoing. It then drops to the impact zone B. The material as it leaves the rotating disc 11a by centrifugal force, impinges against the stationary wearing face 47. It is further acted upon by the hammers 45 supported above the revolving disc 11a. The material as it is impacted by the hammers 45 is driven with considerable force against the pegs or bars 48. The result of these various impact actions will be to reduce the size of the material being treated by impact to a sufficiently small size for removal from the impact zone by the air or gas entering through the opening 46. The air or gas passing through the circumferential opening 46 will effectively prevent any accumulation of material being treated at the outer edge of the rotating disc 11a. The material being treated on leaving the impact zone meets additional air entering the mill through the circumferential opening 51. The further action of classification, attrition, and discharge from the pulverizer, of the material being treated, is identical with that previously described in this specification.
- 35 40 45 50 55 60 The pressure of the air or gas flow developed by the action of the fan-like blades 16 on the underside of the revolving disc 11a will be indicated by the suitable liquid 54 in the U tube or manometer 53. As the density of the mixture of air or gas and material in the impact zone increases, the resistance to the air or gas flow will increase and be indicated. This pressure indication will be useful as a guide to an operator in

the regulation of the supply of material delivered to the pulverizer for treatment. The variation in pressure may if desired be made use of to automatically control the rate at which the feeder delivers material to be treated to the pulverizer. It will be understood that while the use of the tubing 52, and the U tube or manometer 53, will be helpful to an operator for control purposes, that its use is optional, and that its omission will not in any way interfere with the mill functioning as a pulverizer.

5 10 15 20 25 30 35 40 45 50 55 60 What I claim is:

1. A pulverizing mill, comprising a vertically extending housing, a vertically journaled shaft operating therein, an impact pulverizer in the lower portion of said housing and operated by said shaft, said housing having an air inlet below said impact pulverizer and air passages extending upwardly about said impact pulverizer, means for delivering material to be pulverized to said impact pulverizer, an attrition pulverizer above said impact pulverizer and operated by said shaft, a conical wall about the shaft above said attrition pulverizer and forming with the surrounding wall of the housing an air passage for conveyance of the materials reduced by the impact pulverizer and attrition pulverizer, an inverted conical wall above said conical wall for deflecting material carrying air currents downwardly in the conical wall toward said attrition pulverizer, a rotating classifier on the shaft at said inverted conical wall for assisting in classification of fine and coarse particles and for aiding in deflecting the coarse particles into the conical wall, the housing having a discharge passage in the top of the same extending from said inverted conical wall and means for creating upwardly flowing mill air currents through the housing from said inlet at the bottom through said outlet at the top.

2. A pulverizing mill, comprising a vertically extending housing having an air inlet at the bottom and a discharge outlet at the top, an upright shaft rotating in said housing, impact pulverizer elements mounted on the lower portion of the shaft above said air inlet, an attrition pulverizer element on said shaft above said impact pulverizer elements, a conical hopper about said shaft and having its lower end discharging to said attrition element on the shaft, attrition element means supported by the lower end of said hopper in cooperative relation with said attrition element on the shaft, material classifying means above said conical hopper and in communication with the discharge outlet of the housing, said conical hopper and the surrounding wall of the housing forming passages extending upwardly from said impact and attrition pulverizers and downwardly into the upper end of the conical hopper and means for creating a flow of mill air currents from said inlet to said discharge outlet.

JOSEPH B. GAFFNEY.
